UNITED STATES PATENT OFFICE

160,597

SELF-LOCKING TWEEZERS

Marie Louise Hawk, Santa Monica, Calif.

Application March 23, 1949, Serial No. 1,573

Term of patent 7 years

(Cl. D89—10)

To all whom it may concern:

Be it known that I, Marie Louise Hawk, a citizen of the United States, residing in Santa Monica, in the county of Los Angeles and State of California, have invented a new, original, and ornamental Design for Self-Locking Tweezers, of which the following is a specification, reference being had to the accompanying drawing, forming a part thereof.

Figure 1 is a perspective view of self-locking tweezers, showing my new design. The tweezers are illustrated with its jaws in extended position.

Figure 2 is a perspective view similar to Figure 1, but with the jaws in retracted, gripping position.

Figure 3 is a side elevation of the self-locking tweezers of Figures 1 and 2 and showing the jaws thereof in their retracted position.

Figure 4 is a plan view, with the tweezers in extended position.

Figure 5 is a view in end elevation.

I claim:

The ornamental design for self-locking tweezers, substantially as shown.

MARIE LOUISE HAWK.
